Attys.

UNITED STATES PATENT OFFICE

HAROLD MARSH, OF HOPEDALE, MASSACHUSETTS, ASSIGNOR TO DRAPER CORPORATION, OF HOPEDALE, MASSACHUSETTS, A CORPORATION OF MAINE

DOBBY FINGER AND SUPPORT

Application filed July 17, 1929. Serial No. 378,930.

This invention relates to dobbi mechanisms for looms having a plurality of indicating fingers which are operated by a pattern chain to control the operation of the harnesses. In the majority of cases there are a large number of these indicator fingers which must be installed in a limited space. As a result of this condition the fingers are of necessity relatively thin and therefore subject to breakage. For this and various other reasons the fingers must from time to time be replaced or removed. In order to save time and avoid inconvenience it is desirable that when such removal and replacement takes place the remaining fingers shall not be disturbed. It is also desirable that under normal running conditions the fingers have a free acting pivot at their fulcrum point and one that is firm enough to prevent jumping of the fingers when they are lifted by the pins on the pattern chain.

It is the object of this invention to provide a simple and efficient means for mounting the indicator fingers and one which will allow the ready removal and replacement of any finger without interfering with or causing the remaining fingers to get out of adjustment.

A further object of the invention is to secure the above results without the necessity of employing additional elements or temporary supporting means for the remaining fingers when one is to be removed or replaced.

The object of the invention is further to provide a two part shaft upon which the fingers pivot which normally has a true circular cross section, one part of which may be removed separately to provide for removal of the individual fingers leaving the other part as a support.

These and other objects and features of the invention will more fully appear from the accompanying description and drawings and will be particularly pointed out in the claims.

Only that portion of the dobbi mechanism which directly concerns the novel elements is illustrated in the drawings. The general construction of dobbi mechanisms is well known to those skilled in the art and due to

the nature of the invention it may be applied to a variety of dobbi constructions. Hence only a portion of typical dobbi mechanism is shown together with a preferred embodiment of the invention.

In the drawings:

Fig. 1 is a partial view in vertical cross section through a dobbi mechanism illustrating in particular the construction of the pivot point for the indicator fingers.

Fig. 2 is a cross sectional view on line 2—2 of Fig. 1.

Fig. 3 is a detailed view showing the method of removing an indicator finger.

The dobbi comprises the usual frame construction upon which the various elements are mounted. The side members 1 are connected by suitable transverse members which include the usual front bar 2. The indicating fingers 3 are arranged closely together in a transverse group and each are of a similar shape with the exception of their rear portions. As to that portion they have alternately one of two forms of construction. One set of fingers have a straight rear portion 4 which engages lifting rods 5 which in turn control the upper hooks not shown. The rear portion 6 of the other set of fingers are turned upward slightly to directly engage and control the hooks 7. These indicator fingers are actuated by pins 8 upon the usual pattern chain.

The pattern chain is moved by means of a grooved drum 9 upon a shaft 10 which is rotated to bring the pins into contact with the proper fingers which raises the front end thereof causing the rear portion to be depressed thus lowering the hooks 7 into the path of the reciprocating knife 11 which actuates that particular harness connected to the hook in a manner well known to those skilled in the art.

The invention resides chiefly in the method of supporting the fingers within the frame. At their forward ends the fingers rest upon the bar 2 and are fulcrumed upon a specially constructed shaft 12. The center of gravity of each finger is well forward of the fulcrum point so that the forward ends of the fingers normally rest upon the bar 2 by gravity. The shaft 12 is journaled in side frames

1 in cylindrical apertures 13. The shaft itself is composed of two semi-cylindrical portions 14 and 15 which by reason of a snug fit in the journals 13 are maintained in position to form a shaft having a true circular cross section. 5 One end 16 of the shaft sections is bent at substantially 90° to provide a means of readily withdrawing the sections which are normally locked against removal by the pin 17 which extends through both sections. 10

Each finger is provided with a cylindrical aperture 18 of a size to permit free pivotal motion of the finger about the shaft. Extending downwardly from the aperture 18 to the lower edge of the finger preferably at an angle 15 is a slot 19. This slot is of a width to permit a finger to be removed from one of the shaft portions when the other portion has been removed. However the slot is of such a size as 20 to effectually prevent the removal of any finger when the two shaft portions are in place. The extreme simplicity and effectiveness of the device greatly increase the efficiency of the dobby. When the two shaft portions are 25 in place and locked against removal under no circumstances may the fingers be removed. It makes no difference in what position about its axis the shaft 18 may be, each finger at all times will be securely prevented from jumping 30 on the shaft or becoming disengaged therefrom.

As a result of this construction the accuracy 35 of operation of the dobby is greatly increased. This assurance that the device will function positively is obtained at no sacrifice to the smoothness of action of the pivot point of the reason that the fulcrum points consist of cylindrical bearings running upon a true cylindrical shaft.

40 To remove and replace a finger which has been broken or for any reason it is desired to remove a finger it is merely necessary to remove the locking pin 17 and withdraw one of the shaft sections. The remaining section 45 will serve to support the remaining fingers while the faulty one may be withdrawn by lifting it off the shaft. Preferably the shaft is positioned so that it will not be necessary to rotate it to bring the flat sides of the sections 50 parallel with the sides of the slot 19. This may be secured by having the end 16 of the shaft section, as 14, that is to remain in place extend between lugs 20 on the side frame member 1 and by having a cotter pin 21 in the 55 lugs. This will position both shaft sections but leave one section, as 15, free to be withdrawn while the section 14 will remain in the position required for removal and replacement of the fingers. This section 14 will pass 60 through the slot as the finger is lifted off and a new one may then be replaced thereon.

65 While, as illustrated, the shaft portions are shown of semi-cylindrical cross section, these two portions may present different segmental cross sections so long as they together form

an outer cylindrical shaft and the slots in the indicating fingers may be made of a width to correspond with the thickness of either segmental portion.

Having thus described the invention, what 70 is claimed as new and desired to be secured by Letters Patent, is:

1. In a loom dobby the combination of a frame, a fulcrum shaft journalled in the frame sides and comprising two substantially 75 semi-cylindrical portions held by the journals in position to form a cylindrical shaft, and a series of indicating fingers fulcrumed on said shaft each having a cylindrical aperture, of a size to fit said shaft, at its fulcrum point with a slot extending therefrom to the lower edge of the finger, said slot being of a width substantially equal to one-half the diameter of said shaft, whereby upon removal of one of the semi-cylindrical shaft 80 portions any finger may be removed and replaced without disturbing the remainder. 85

2. In a loom dobby having the construction defined in claim 1, the combination therewith of means to lock said shaft against removal. 90

3. In a loom dobby having the construction defined in claim 1, the combination therewith of means to lock the two semi-cylindrical shaft portions against relative longitudinal motion. 95

4. In a loom dobby having the construction defined in claim 1, the combination therewith of means to lock against rotation the shaft section which is not to be removed whereby it is always in position to enable the fingers 100 readily to be removed and replaced when the other shaft portion is withdrawn.

5. In a loom dobby the combination of a frame, a fulcrum shaft journalled in the sides of the frame and comprising two substantially semi-cylindrical shaft portions held by the journals in position to form a cylindrical shaft and having their ends extending beyond the limits of the frame at one side and bent at substantially 90° to the axis of the 105 shaft to provide means to readily grasp and remove these shaft portions, and a series of indicating fingers fulcrumed on said shaft each having at its fulcrum point a cylindrical aperture of a size to fit said shaft with a slot 110 extending therefrom to the lower edge of the finger, said slot being of a width substantially equal to one-half the diameter of the shaft, whereby upon removal of one of the semi-cylindrical shaft portions any finger 115 may be removed and replaced without disturbing the remainder. 120

6. In a loom dobby the combination of a frame, a fulcrum shaft journalled in the frame sides and comprising two segmental portions held by the journals in position to form a cylindrical shaft, and a series of indicating fingers fulcrumed on said shaft, each having a cylindrical aperture of a size 125 to fit said shaft at its fulcrum point with a 130

slot extending therefrom to the lower edge of the finger, said slot being of a width substantially equal to the thickness of one of the segmental shaft portions, whereby upon the removal of the other segmental shaft portion any finger may be removed and replaced without disturbing the remainder.

7. A loom having the construction defined in claim 6 together with means for locking the first segmental shaft portion against rotation with its flat side parallel to the walls of the slots in the fingers when the fingers are in normal position.

In testimony whereof, I have signed my name to this specification.

HAROLD MARSH.
